United States Patent Office.

DANIEL E. TEAL, OF NORWICH, NEW YORK.

Letters Patent No. 90,701, dated June 1, 1869; antedated May 19, 1869.

IMPROVED SPRING ROCKING-CHAIR.

The Schedule referred to in these Letters Patent and making part of the same.

To all whom it may concern:

Be it known that I, DANIEL E. TEAL, of Norwich, in the county of Chenango, and State of New York, have invented a new and improved Spring Rocking-Chair; and I do hereby declare that the following is a full, clear, and exact description thereof, reference being had to the accompanying drawings, and to the letters of reference marked thereon, making a part of this specification.

Figure 1 is a side elevation.

Figure 2 is a plan, or bottom view reversed.

Similar letters of reference indicate like parts in all of the figures.

The nature of my invention consists in the construction of a chair, provided with springs, attached to a frame, or spider between the bottom of the chair and the stool, so arranged as to allow the chair to rock, or tilt back, without rocking forward, at the option of the sitter.

To enable others skilled in the art to make and use my invention, I will now proceed to describe its construction and operation.

I take any kind of chair in use, and to the seat, or bottom of the chair A is attached an iron, frame, or spider, B, fastened with screws.

At or near the centre of the spider is a box, or mortise, C, which is made rectangular in form.

The object of the box, or mortise is to receive the end of a shaft, D, which is attached to the stool of the chair. At the upper end of the shaft is a pivot, connecting the stool to the seat.

In front, and back of the shaft, inside of the box, or mortise, are springs F F, to keep the shaft in the centre of the mortise, also to give a rocking motion to the chair when desired, at the option of the sitter.

G G are holes in the box, or mortise, for the insertion of pivots, to keep the chair from rocking forward or backward, when desired.

Having thus described my invention,

What I claim, and desire to secure by Letters Patent, is—

1. The box, or mortise C, when used in connection with the shaft D, as and for the purpose specified.

2. The combination of spider B, box, or mortise C, shaft D, and springs F F, as and for the purpose herein described.

DANIEL E. TEAL.
